UNITED STATES PATENT OFFICE.

WALDO A. LAYMAN, OF ST. LOUIS, MISSOURI.

DESIGN FOR AN ELECTRICAL-INSTRUMENT CASE.

SPECIFICATION forming part of Design No. 29,451, dated October 4, 1898.

Application filed July 14, 1898. Serial No. 685,954. Term of patent 14 years.

To all whom it may concern:

Be it known that I, WALDO A. LAYMAN, a citizen of the United States, residing at the city of St. Louis, in the State of Missouri, have invented and produced a new and original Design for an Electrical-Instrument Case, of which the following is such a full, clear, and exact description as will enable any one skilled in the art to which it appertains to make and use the same, reference being had to the accompanying drawings, forming part of this specification.

In the accompanying drawings, wherein my new and useful design is shown and wherein like marks of reference refer to the same parts, Figure 1 is a top plan view. Fig. 2 is a side elevation. Fig. 3 is a bottom plan view, and Fig. 4 is a front elevation.

I will now describe the leading features of my design.

10 is the front plate of the case, from which

a curved portion 11 projects forwardly. In the part 11 is an oblong opening 12, and in the lower part of the plate 10 is an oblong opening 13. Extending rearwardly from the upper part of the plate 10 is a thin tapering portion 14, which terminates in a cylindrical part 15. Secured to the rear of the cylindrical part 15 is a block 16, to which are secured suitable binding-posts 17.

Having fully described my invention, what I claim, and desire to secure by Letters Patent of the United States, is—

The design for an electrical-instrument case, substantially as shown and described.

In testimony whereof I have hereunto set my hand and seal in the presence of the two subscribing witnesses.

WALDO A. LAYMAN. [L. s.]

Witnesses:

A. C. FOWLER,
W. A. ALEXANDER.
